US0D1102741S

(12) United States Design Patent (10) Patent No.: US D1,102,741 S
(45) Date of Patent: * Nov. 25, 2025

(54) RUCKSACK

(71) Applicant: G.T. LINE—S.R.L., Frazione Crespellano (IT)

(72) Inventor: Massimo Tonelli, Bologna (IT)

(73) Assignee: G.T. LINE—S.R.L., Frazione Crespellano (IT)

() Term: 15 Years

(21) Appl. No.: 29/958,721

(22) Filed: Aug. 21, 2024

(30) Foreign Application Priority Data

Feb. 26, 2024 (EM) 015051925-0009

(51) LOC (15) Cl. 03-01

(52) U.S. Cl.

USPC D3/217
